UNITED STATES PATENT OFFICE.

FRED B. KING AND HARRY W. LINDSEY, JR., OF TOLEDO, OHIO, ASSIGNEES, BY MESNE ASSIGNMENTS, TO THE WILLYS-OVERLAND COMPANY, OF TOLEDO, OHIO, A CORPORATION OF OHIO.

SEAT STRUCTURE.

Application filed March 18, 1920. Serial No. 366,835.

Our invention relates to improvements in seat structures and is particularly directed to the construction of seats for automobiles and other vehicles.

5 One object of the invention is to provide improved means for tying and bracing the border frame of a seat unit.

A further object of the invention is to provide improved means for securing the 10 ends of transverse ties extending between the sides of a border frame.

A further object of the invention is to provide improved means for securing the 15 ends of a plurality of transversely extending wires upon the sides of a border frame in such a manner as to produce a rigid supporting structure.

A further object of the invention is to provide new and improved means for anchoring the ends of transversely extending 20 wires upon the opposite sides of a frame and to so construct the ends of the wires and that portion of the frame with which they are connected as to prevent the turning or twisting of the wires regardless of 25 the manner in which they are anchored.

A further object of the invention is to provide a new and improved method of assembling and anchoring a plurality of 30 transverse tie members upon the opposite sides of a metal band to produce a frame unit upon which the upholstery of the seat may be quickly secured.

Still another object of the invention is to 35 provide a frame between the opposite sides of which are first assembled a plurality of transversely extending members for tying the sides of the frame together and thereafter forming upon the frame a plurality of 40 anchors for holding the transverse members in the desired position so that they will constitute means for tying and bracing the sides of the frame to form a rigid supporting structure.

45 Another object of the invention is to provide a seat frame of simple construction which can be manufactured at a relatively low cost and which will afford a strong and durable construction capable of withstand- 50 ing severe strains and stresses.

Further objects of the invention relate to economies of manufacture and details of construction as will hereinafter appear from the detailed description to follow.

The objects of the invention are accomplished in one instance by the devices and means described in the following specification, but it is evident that the same may be varied without departing from the scope of the invention as pointed out in the appended claims.

A structure constituting one embodiment of the invention is illustrated in the accompanying drawings forming a part of the specification in which:

Figure I is a fragmentary view in perspective illustrating the improved manner of connecting the ends of the frame tie members with the side portions of the frame.

Figure II is a fragmentary sectional elevation of a seat construction embodying the invention.

Figure III is an enlarged detailed fragmentary sectional view taken through the 75 base of the seat at one side thereof.

Figure IV is a fragmentary sectional plan showing the manner of assembling the transversely extending tie members upon the border frame previous to forming the 80 anchors thereon to hold said members in the desired position and;

Figure V is an enlarged detailed section taken on line 5—5 of Figure II.

In the drawings similar reference characters designate corresponding parts throughout the several views.

In the embodiment of the invention as illustrated herein, 10 indicates a border frame or band of metal which may be rectangular in form or of any other desired shape depending upon the shape of the seat to be supported by said frame. The upstanding plate portion of the frame is provided with the upper and lower outwardly 90 extending flange portions 11 and 12 comprising generally a U-shaped member formed by the use of a suitable die, whereby a groove is provided for receiving the ends of the wire meshing comprising the 95 transversely extending interwoven corrugated wires 13 and 14 as best shown in Figures III and IV.

The ends of the wires are provided with the right angle bent portions 15 which lie within and extend longitudinally of the groove formed by the flanged portions 11 and 12 of the frame and said portions 15

are preferably turned inwardly at 16 to extend parallel with the main body portion of the wire at a suitable distance therefrom to more effectively prevent the turning or twisting of the wires when assembled within the frame. The ends of the wires are anchored within the groove by means of the inwardly extending lugs or projections 17 as best shown in Figure V and these projections are formed by the use of a suitable tool, such as a punch which is preferably driven into or through the upper flange portion 11 of the frame to force the metal down into engagement with the bent portion 15 of the wire. During this operation the frame is allowed to rest upon a suitable base or support and the punch is driven through the flange 11 from the outside thereof at a point substantially where the bend is made between the upstanding portion of the frame and said flange. The inwardly extending anchors or boss-like projections 17 may be quickly formed by this method after the frame has been practically completed and such means serves as a very effectual method of anchoring the ends of the wires upon the frame to prevent the spreading of the sides of the frame when the load is applied thereto.

We have found in practice that it is not necessary to provide the anchors 17 at both ends of each wire for the reason that the interlacing of the wires particularly when in corrugated form prevents them from being displaced one upon another as each wire is firmly held by those crossing it. A great saving in the cost of manufacture is effected by constructing the seat frame unit in this manner since only one half as many operations are required for securing the ends of the wires by this method as might otherwise be necessary. While in the assembling of the wire meshing within the frame we prefer to first construct the frame as a continuous and unbroken band, the sides of which are sprung apart to permit the bent ends of the wires to be inserted within the groove, it will be understood that the ends of the band may be left open or unconnected until after the wire mesh has been assembled in the manner shown in Figure IV, after which the loose ends of the band may be connected in any suitable manner such as by spot-welding, or if desired the band may be constructed of several unconnected sections and applied to the wire mesh and the several sections may then be tied together in any suitable manner such as by riveting or spot-welding or in any other preferred manner.

Any desired superstructure may be placed upon the wire-mesh but we prefer to employ a structure similar to that shown in Figure II in which a plurality of relatively small coil springs 18 are positioned in suitable pockets 19 and enclosed in a flexible casing

20 of cloth or other suitable material which is preferably provided at its lower side with a border wire 21 serving to stiffen and strengthen the casing to a certain degree. The casing with the individually enclosed 70 springs mounted therein is then placed upon the wire mesh as shown in Figure II. A top border frame 22 of suitable construction is placed upon the casing 20 containing the springs 18 and super-imposed thereon 75 is a cushion 23 having a covering 24 provided with a downwardly extending apron 25 at the bottom edge of which is provided a pocket for receiving a cord or wire 26 serving to provide a bead upon the lower 80 edge of the apron, said bead being engaged by a plurality of tongues 27 struck outwardly from the frame member, it being understood that after the bead is inserted behind the tongues the same will be forced 85 inwardly as shown in Figure III to secure the bottom of the apron upon the border frame.

While the structure shown and described herein is well adapted to fulfill the objects 90 of the invention, it will be understood that certain changes in the form, proportions and arrangement of parts may be resorted to, without departing from the spirit of the invention and therefore we do not limit the 95 invention to the specific design and construction shown and described except in so far as said construction may be limited by the terms of the following claims in which it is our intention to claim all novelty inherent 100 in the invention, broadly as well as specifically.

What we claim as new and desire to secure by Letters Patent is:

1. In a device of the class described, a 105 frame comprising a band of metal formed by bending a plate to provide top and bottom substantially parallel flange portions forming an inwardly opening groove, said top flange portion being bent upwardly substantially in line with the extremity of said bottom flange portion, a plurality of transverse tie members having their ends bent and disposed within said groove and lugs struck downwardly from said top flange 115 portion into retaining engagement with the bent ends of said transverse tie members.
2. In a device of the class described, a 120 frame comprising a band of metal formed by bending a plate to provide top and bottom substantially parallel flange portions forming an inwardly opening groove, said top flange portion being bent upwardly substantially in line with the extremity of said bottom flange portion, a plurality of transverse tie members having their ends bent and disposed within said groove, lugs struck downwardly from said top flange portion 125 into retaining engagement with the bent ends of said transverse tie members, springs 130

disposed upon said tie members, upholstery carried by said springs and an apron depending from the upholstery and secured upon the upwardly bent portion of said top flange.

3. In a device of the class described, a frame comprising a band of metal having an upstanding wall, the lower portion of which is bent outwardly and thence inwardly to form a channel-shaped base for the frame, a plurality of transverse tie-members having bent end portions disposed within the channel, and projections struck inwardly from one wall of the channel by driving a tool into the metal at points intermediate the edges of the band whereby to engage said end portions and secure them to the band.

4. In a device of the class described, a frame comprising a band of metal having an upstanding wall, the lower portion of which is bent outwardly and thence inwardly to form a channel-shaped base for the frame, a spring supporting unit comprising a plurality of interwoven wires having their ends bent and disposed within said channel, and projections struck inwardly from one wall of the channel by driving a tool into the metal at points intermediate the edges of the band, whereby to engage and secure certain of the bent ends of said wires.

In testimony whereof they affix their signatures.

FRED B. KING.
